US0D1071386S

(12) **United States Design Patent** (10) **Patent No.:** **US D1,071,386 S**
(45) **Date of Patent:** **** Apr. 15, 2025**

(54) **FIRE EXTINGUISHER**

(71) Applicant: **X-SENSE USA LLC**, Wilmington, DE
(US)

(72) Inventor: **Yiming Zhang**, Shenzhen (CN)

(**) Term: **15 Years**

(21) Appl. No.: **29/970,139**

(22) Filed: **Oct. 25, 2024**

(51) **LOC (15) Cl.** **29-01**

(52) **U.S. Cl.**

(57) **CLAIM**

The ornamental design for a fire extinguisher as shown and described.

DESCRIPTION

FIG. 1 is a perspective view of a fire extinguisher showing my new design;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The dash-dash broken lines in the drawings depict portions of the fire extinguisher that form no part of the claimed design.

1 Claim, 8 Drawing Sheets
